US0D1079612S

(12) **United States Design Patent** (10) **Patent No.:** **US D1,079,612 S**
(45) **Date of Patent:** **** Jun. 17, 2025**

(54) **ELECTRIC VEHICLE CHARGING STATION**

(71) Applicant: **ChargePoint, Inc.**, Campbell, CA (US)

(72) Inventors: **Justin D. Cumming**, Winthrop, ME (US); **David Hoenig**, Los Gatos, CA (US); **Pasquale Romano**, Los Gatos, CA (US); **Kevin Fetterman**, San Jose, CA (US); **William Rich**, Emerald Hills, CA (US); **Jonathan Christopher Wilson**, San Jose, CA (US); **Stephen Eric Sidle**, Morgan Hill, CA (US); **John Hsudan Yu**, Fremont, CA (US); **Jacob Heth**, Lodi, CA (US); **Stan C. Reyes**, San Jose, CA (US)

(73) Assignee: **CHARGEPOINT, INC.**, Campbell, CA (US)

(**) Term: **15 Years**

(21) Appl. No.: **29/865,545**

(22) Filed: **Jul. 29, 2022**

(51) LOC (15) Cl. **13-02**

(52) U.S. Cl.

CLAIM

The ornamental design for an electric vehicle charging station as shown and described.

DESCRIPTION

FIG. 1 shows a front perspective view of an electric vehicle charging station showing the claimed design;

FIG. 2 shows a front view thereof;

FIG. 3 shows a back view thereof;

FIG. 4 shows a right view thereof;

FIG. 5 shows a left view thereof;

FIG. 6 shows a top view thereof;

FIG. 7 shows a bottom view thereof; and,

FIG. 8 shows a rear perspective view thereof.

The broken lines illustrate environmental structure and/or portions of the electric vehicle charging station that form no part of the claimed design.

1 Claim, 7 Drawing Sheets
